UNITED STATES PATENT OFFICE.

CHARLES M. BULLER, OF MILWAUKEE, WISCONSIN, ASSIGNOR TO L. J. MUELLER FURNACE COMPANY, OF MILWAUKEE, WISCONSIN, A CORPORATION OF WISCONSIN.

ADJUSTABLE BOOT FOR PIPES.

Application filed May 6, 1921. Serial No. 467,394.

To all whom it may concern:

Be it known that I, CHARLES M. BULLER, a citizen of the United States, and resident of Milwaukee, in the county of Milwaukee, 5 and State of Wisconsin, have invented new and useful Improvements in Adjustable Boots for Pipes, of which the following is a description, reference being had to the accompanying drawings, which are a part 10 of this specification.

This invention relates to improvements in adjustable boots for pipes.

In heating buildings with hot air furnaces, it is the usual practice to extend 15 round pipes from the furnaces in the cellars to the partition walls and connect said pipes to vertical rectangular pipes which extend upwardly through the partitions to the respective rooms to be heated. While the 20 round pipes are of a standard size, the rectangular pipes differ in cross sectional area, due to the different widths of studding and the size of register used. The round pipes are connected to the rectangular pipes by 25 fittings called boots which, in the ordinary construction, vary in size to fit the different sized rectangular pipes.

It is one of the objects of the present invention to provide an adjustable boot for 30 pipes which may be easily adjusted to fit rectangular pipes of various sizes.

A further object of the invention is to provide an adjustable boot for pipes which, when adjusted, will be maintained in said 35 adjusted position.

A further object of the invention is to provide an adjustable boot for pipes which is of simple construction, is strong and durable, and is well adapted for the purpose 40 described.

With the above and other objects in view, the invention consists of the improved adjustable boot for pipes and its parts and combinations as set forth in the claims, and 45 all equivalents thereof.

In the accompanying drawing, in which the same reference characters indicate the same parts in all of the views:

Fig. 1 is a side view of the improved adjustable boot for pipes shown mounted on the upper end of a round pipe;

Fig. 2 is a top view thereof on a larger scale;

Fig. 3 is a vertical sectional view taken

on line 3—3 of Fig. 2, showing the parts 55 secured in their final position and a portion of a rectangular pipe connected thereto;

Fig. 4 is a sectional detail view of the upper end portion of the boot before securing the parts in final position; and

Fig. 5 is a sectional detail view on a larger scale, taken on line 5—5 of Fig. 3.

Referring to the drawings, the numeral 8 indicates an annular collar adapted to telescope over the upper end of a round pipe 65 9 which is connected to the furnace (not shown). The collar is of the elbow type, and its upper or boot portion 10 is angled upwardly and notched or recessed as at 10' and forms a rectangular opening 11 at its 70 upper end. One portion 12 of the side wall adjacent the notched part of the upper open part 11, is bent inwardly to form a part closure as clearly indicated by the said numeral 12 in Fig. 4, and its opposite side 75 edge portions 13 extend over the upper notched edges 10' and the said projecting edge portions 13 are flanged downwardly, as clearly shown in Fig. 5, and the flanged portions are slit, as indicated by the numeral 15, so that the closure part 12 may 80 easily be bent upwardly as indicated by the numeral 12'.

Front and side angular strips 16 and 17 are crimped over the upper front and side edges of the boot, and depend 85 downwardly therefrom to form receiving grooves 18 and 19 extending at right angles to each other. Only the front portions 17' of the side strips 17 are crimped over the upper edge portions of the boot part 10 90 while the rear portions of said side strips 17 are spaced from the notched portions 10' of the boot to form slots 14, and are secured to the side portions of the part by soldering, as indicated by the numeral 20. A rear 95 angular strip 21 adjustably mounted on the closure part 12 is of U-shape in cross section, and is provided with forwardly projecting side guide members 22 which close the notches or recesses 10' of the boot part 10, 100 and at their upper edge portions 22' extend over the upper edges of the boot part 10.

The lower edge portions of the guide members 22 extend through the elongated slots 14 and are bent outwardly to form 105 flanges 23 beneath the side strips 17. The rear angular strip forms a rear groove 24 which, in combination with the grooves 18

and 19, form a rectangular grooveway to receive the lower rectangular portion of a vertical pipe or stack 25.

In use the rear angular strip 21 is adjusted forwardly or rearwardly to decrease or increase the width of the rectangular grooveway, and when adjusted to fit the lower end of the vertical pipe 25, the inner edge portion of the closure 12 is bent upwardly, as shown by 12' in Fig. 3, to increase the size of the opening 11, the slit flange portions 13 of the closure permitting the easy bending of the closure portion. Said bent portion serves to hold the rear angular strip in adjusted position.

It is to be understood that the adjustable boot is adapted for use with single or double wall vertical stacks.

From the foregoing description it will be seen that the improved boot may be easily adjusted to fit rectangular pipes of various widths.

What I claim as my invention is:

1. An adjustable boot for pipes, comprising a collar having one end portion of rectangular shape in cross section and a side wall extending inwardly, angular strips forming grooves mounted on three sides of the rectangular portion, and an angular strip adjustably mounted on the fourth side of the rectangular portion and resting on the inwardly extending side wall to form in connection with the other angular strips a rectangular grooveway to receive one end portion of another pipe.

2. An adjustable boot for pipes, comprising a collar having one end portion of rectangular shape in cross section and a bendable inwardly extending side wall, angular strips forming grooves mounted on three sides of the rectangular portion, and an angular strip adjustably mounted on the upper side of the bendable side wall portion and having end portions which are flanged outwardly and beneath the side angular strips, said angular strips forming a grooveway extending around the boot, said inwardly extending side wall adapted to be bent upwardly alongside of the adjustable strip.

3. An adjustable boot for pipes, comprising a collar having one end portion extending at an angle to the collar and being of rectangular shape in cross section, one of the side walls of the rectangular part extending inwardly and partly covering the rectangular opening of said end, opposite side walls of said rectangular part having upper notched portions, angular strips forming

grooves mounted on three sides of the rectangular portion, said strips on opposite sides being in part spaced from the side walls to form elongated slots, and an angular strip adjustably mounted on the upper side of the inwardly extending part and having opposite end-portions which extend through the elongated slots and are flanged outwardly, said angular strips forming a grooveway extending around the boot, said inwardly extending side wall adapted to be bent upwardly alongside of the adjustable strip when said strip is adjusted in position.

4. An adjustable boot for pipes, comprising a round collar having one end portion extending upwardly at an angle from the collar and being of rectangular shape in cross section, one of said side walls of the rectangular part extending inwardly and partly covering the rectangular opening of said end, opposite side walls of said rectangular part having upper notched portions, front and side angular strips having upper bent portions which extend over and are secured to the upper edges of the rectangular portion, said strips on opposite sides being in part spaced from the side walls to form elongated slots, and an angular strip slidably mounted on the upper side of the inwardly extending part and having opposite end guide portions which overlap upper side edges of the rectangular part and having also other end portions which extend downwardly through the elongated slots and are flanged outwardly beneath the side angular strips, said angular strips forming a grooveway extending around the boot and said inwardly extending side wall adapted to be bent upwardly alongside of the adjustable strip when said strip is in adjusted position.

5. An adjustable boot for pipes, comprising a collar having one end portion of rectangular shape in cross section and a bendable inwardly extending side wall, angular strips mounted on three sides of the rectangular portion, and an angular strip adjustably mounted on the upper side of the bendable side wall portion and having end portions which are flanged outwardly and beneath the side angular strips, said inwardly extending side wall adapted to be bent upwardly alongside of the adjustable strip.

In testimony whereof I affix my signature.

CHARLES M. BULLER.
